CHILD'S ROCKING CHAIR

Arthur P. Snyder, 5315 W. 13th Ave., Denver, Colo.

Filed Sept. 26, 1960, Ser. No. 62,262

Term of patent 3½ years

(Cl. D15—6)

Fig. 1

Fig. 2

FIG. 1 is a perspective view of a child's rocking chair showing my new design; and

FIG. 2 is a rear elevational view thereof.

The side of the chair opposite to that shown in FIG. 1 is exactly similar to the side illustrated.

I claim:

The ornamental design for a child's rocking chair, as shown and described.
